Primary Examiner — Ian Simmons*Assistant Examiner* — Dana L Sipos(74) *Attorney, Agent, or Firm* — QuickPatents, Inc.; Kevin Prince(57) **CLAIM**

I claim the ornamental design for a bottle and lid, as shown and described.

DESCRIPTION

FIG. 1 is a top, front, right side perspective view of a bottle and lid, showing my new design;

FIG. 2 is an exploded top, front, right side perspective view thereof;

FIG. 3 is an exploded front elevational view thereof;

FIG. 4 is an exploded rear elevational view thereof; and,

FIG. 5 is an exploded right-side elevational view thereof, the left-side elevational view being a mirror image thereof.
